UNITED STATES PATENT OFFICE.

HUGH DYER, OF NECK CITY, MISSOURI.

HOISTING APPARATUS.

SPECIFICATION forming part of Letters Patent No. 739,843, dated September 29, 1903.

Application filed May 28, 1903. Serial No. 159,068. (No model.)

To all whom it may concern:

Be it known that I, HUGH DYER, a citizen of the United States, residing at Neck City, in the county of Jasper and State of Missouri, ⁵ have invented a certain new and useful Improvement in Hoisting Apparatuses, of which the following is a specification.

My invention relates to hoisting apparatus, and has for its object to provide a new and ¹⁰ improved hoisting device, of which the following is a description, reference being had to the accompanying drawings, wherein—

Figure 1 is a plan view of a hoisting device embodying my invention. Fig. 2 is a longitudinal section through the same. Fig. 3 is a section on line 3 3 of Fig. 1.

Like letters refer to like parts throughout the several figures.

Referring now to the drawings, the hoisting-²⁰ drum A is loosely mounted on a shaft B, supported in or upon a suitable frame. The shaft B is operatively connected to a driving-shaft C in any desired manner, as by means of the gears B' C'. This driving-shaft is connected in any desired manner with a source ²⁵ of power. This shaft may be driven by horse-power, belts, engines, motors, or the like. The drum A is provided at each end with the engaging faces A', which are preferably inclined, as shown, and is mounted between the gear-wheel B' and the disk A². This disk and the gear-wheel B' are each provided with an engaging part A³, which is preferably cone-shaped and which engages the engaging faces ³⁰ A' on the drum. These engaging parts A³ may be of wood or suitable metal or other material, and when they engage the drum A said drum is held between them, so as to rotate with the shaft B. The disk A² is preferably keyed or feathered to the shaft B, so as to rotate therewith, but have a longitudinal movement, and suitable springs A⁴ within the drum normally tend to separate the gear B' and the disk A², so as to release the drum A.

In proximity to the disk A² is a sleeve D, ⁴⁵ loosely mounted on the shaft B and provided with a holding device which prevents its turning with the shaft. As herein illustrated, this object is attained by providing the sleeve D with a projection D', which engages a holding-piece D², attached to the frame. The sleeve D is provided with a left-hand screw-

thread. In proximity to this sleeve is another sleeve E, loosely mounted on the shaft and fixed against rotation by connection with the frame, said sleeve being provided with a right-hand screw-thread. A controlling part or nut F surrounds the shaft B and engages the screw-threads on the sleeves D and E. This controlling part or nut is so arranged ⁶⁰ that when rotated in one direction it moves the two sleeves apart and when rotated in the opposite direction it moves the two sleeves toward each other. This nut is provided with a projection F', which forms the controlling-⁶⁵ lever. As herein shown, the projection F' has attached to it a lever or piece F², by means of which its position can be readily controlled. The controlling part or nut F is also provided with an eccentric F³, which is preferably integral therewith. The strap F⁴ of this eccentric is connected to an arm F⁵ on a sleeve G, loosely mounted on the shaft C. This sleeve G is free to move longitudinally and is provided with the cranks or arms G', to ⁷⁵ which are connected the brake-straps G², which extend around the drum A, said drum being preferably provided with grooves G³ for said straps. These brake-straps G² may be lined with wood or other suitable friction ⁸⁰ material, and the grooves on the drum may also be lined with such material.

It will be noted that each arm G' has parts which project on opposite sides of the shaft, and that one end of each brake-strap G² is ⁸⁵ connected to the arm on one side of the shaft and the other end is connected to said arm on the opposite side of said shaft. It will be seen that by means of this construction the brake-straps may be tightened and loosened ⁹⁰ by rocking the sleeve G through the agency of the arm or lever F⁵. If, for example, said sleeve is rocked in one direction, the straps are loosened, and if rocked in the other direction the straps are tightened, so as to act ⁹⁵ as brakes. The drum A is also preferably provided with a separate brake, which, as herein shown, consists of the brake-strap H, adapted to engage the projecting annulus H' on the drum, said strap being connected to the arm H² on the rocker-shaft H³. This brake-strap H may be lined with wood or other friction material. The rocker-shaft H³ is controlled by means of the lever H⁴, pref-

erably placed so as to be controlled by the foot.

It will be noted that I have here a hoisting device which is simple in construction and which may be made cheaply and which is reliable and efficient in its operation, giving the operator perfect control of the parts.

I have described in detail a particular construction embodying my invention; but it is of course evident that the several parts may be varied in many particulars and that some of the parts may be omitted and others used with parts not herein shown without departing from the spirit of my invention, and I therefore do not limit myself to the device illustrated.

The use and operation of my invention are as follows: When it is desired to operatively connect the drum A with the shafts B and C, and hence with the source of power, the controlling part or nut F is moved so as to separate the sleeves D and E. This result is obtained by moving the controlling-lever F² toward the shaft C—that is, toward the position shown in dotted lines in Fig. 1. This movement of the controlling part or nut F forces the disk A² toward the drum and the drum A toward the gear-wheel B', the drum being clamped between said disk and gear-wheel by means of the cones and inclined faces. Since the disk and gear-wheel are operatively connected to the shaft B, it will be seen that said drum will also be operatively connected with said shaft and will be rotated to wind the rope thereon. The movement of the controlling part or nut F toward the position shown in dotted lines in Fig. 1 causes the sleeve G to be moved or rocked so as to loosen the brake-straps G², this movement being due to the eccentric F³ and the connecting part F⁴. If now it is desired to hold the drum in any given position, the controlling part F is moved, by means of the controlling-lever, to the position shown in full lines in Fig. 1. This movement separates the sleeves D and E, and the spring A⁴ moves the disk A² and drum A to the left, so as to release said drum from the shaft B. This movement of the controlling part also moves or rocks the sleeve G, so as to tighten the brake-straps G² and apply the brake to the drum. It will be noted that the brake-straps G² are not attached to a fixed point on the frame, but are connected with the sleeve G, which is free to move longitudinally, and hence the parts readily adjust themselves to the movement of the drum. There is therefore no danger of breaking the straps or injuring the parts when the brake is suddenly applied. In order to insure the drum remaining stationary while the controlling-lever is being thrown past the central point, I prefer to provide an auxiliary brake. This auxiliary brake is operated by placing the foot on the lever H⁴, thus tightening the brake-strap H, so as to bring it into contact with the projection or annulus H' on the drum. As

soon as the controlling-lever has passed the central point this auxiliary brake may be released. It is of course evident that the auxiliary brake might be omitted and the desired results obtained by throwing the lever F² very quickly from one position to the other. If now it is desired to lower the bucket, cage, or other device connected with the rope on the drum, the controlling-lever F² is moved so as to rock the sleeve G and release the brake-straps G². The weight of the bucket or other device is then free to act to rotate the drum A. It will be seen that this rotation may be controlled, so as to lower at any desired speed, by varying the position of the controlling-lever F², thus varying the force with which the brake is applied to the drum.

In the construction herein illustrated the controlling-lever stays in any position in which it is placed without any holding device, such as ratchets or the like, and the danger and inconvenience of such holding devices are obviated. It will also be seen that by this construction the drum is started, stopped, or reversed without stopping or in any manner controlling the driving-shaft, and that these several operations are all performed by a single controlling-lever. It will further be noted that the controlling parts are all in line with the drum and mounted upon the same shaft.

It will be noted that one of the springs A⁴ engages a part on the drum and the gear B', while the other spring engages a part on the drum and the disk A². It will thus be seen that when the controlling part is operated to move the sleeves D and E toward each other the springs are free to act, and they move the drum A longitudinally, so that it becomes disengaged from the part A³, and they also move the disk A² longitudinally, so that it becomes disengaged from the drum.

I claim—

1. A hoisting device, comprising a shaft, a drum loosely mounted thereon, connecting mechanism for operatively connecting the drum with the shaft, a controlling device for said connecting mechanism, comprising a sleeve mounted on said shaft and provided with a screw-thread, a nut surrounding the shaft and engaging said screw-thread, so that when the nut is rotated the sleeve is moved along the shaft, an eccentric on said nut, provided with an eccentric-strap, and a braking device for said drum, said braking device connected with said eccentric-strap so as to be moved thereby.

2. A hoisting device, comprising a shaft, a drum loosely mounted thereon, a brake-strap therefor, said brake-strap connected to a longitudinally-movable part free to move so as to adjust itself to the position of the drum.

3. The combination with a shaft of two sleeves loosely mounted on said shaft and provided with means for holding them against rotation, said sleeves also provided with oppositely-inclined screw-threads, a nut sur-

rounding said shaft and engaging the screw-threaded ends of said sleeves, so that when the nut is rotated in one direction the sleeves will be separated and when rotated in the other direction the sleeves will be moved toward each other.

4. The combination with a shaft of two sleeves loosely mounted on said shaft and provided with means for holding them against rotation, said sleeves also provided with oppositely-inclined screw-threads, a nut surrounding said shaft and engaging the screw-threaded ends of said sleeves, so that when the nut is rotated in one direction the sleeves will be separated and when rotated in the other direction the sleeves will be moved toward each other, and an eccentric on said nut provided with a strap connected with a movable part.
5. A controlling device for hoisting apparatus, comprising a nut having an eccentric integral therewith and a projecting part also integral therewith, by means of which the position of the nut is controlled.
6. A hoisting device, comprising a shaft, a drum loosely mounted thereon, a connecting mechanism for connecting the drum with the shaft, a controlling device for said connecting mechanism, said controlling device mounted on said shaft, a brake controlled by said controlling device, and an auxiliary brake for said drum independently controlled.
7. A hoisting device, comprising a shaft, a drum loosely mounted thereon, a connecting device at each end of said drum, said connecting devices operatively connected with said shaft, two sleeves loosely mounted on said shaft and provided with holding devices to hold them against rotation, said sleeves provided also with oppositely-inclined screw-threads, a nut surrounding said shaft and engaging the screw-threads on said sleeves, so as to move the sleeves relatively when rotated and thus control the relative position of the connecting devices, an eccentric on said nut, a driving-shaft having a sleeve loosely mounted thereon and connected with the strap of said eccentric, so as to be rocked when the nut is rotated, a brake-strap engaging said

drum and having its ends connected with said sleeve, so as to be tightened or loosened by the rocking of the sleeve.

8. A controlling device for hoisting apparatus comprising a nut for controlling the hoisting-drum and having an eccentric thereon and means for rotating said nut.

9. A controlling device for hoisting apparatus comprising a drum, means for moving the drum longitudinally, a brake for the drum comprising a strap associated with the drum, a shaft carrying a sleeve loosely mounted thereon, said sleeve provided with an arm projecting on opposite sides thereof, one end of said strap connected to said arm on one side of the sleeve and the other end connected to said arm on the other side of said sleeve and means for rocking said sleeve so as to tighten or loosen the strap.

10. A hoisting device comprising a shaft, a drum loosely mounted thereon, a connecting mechanism for operatively connecting the drum with the shaft, a controlling device for controlling said connecting mechanism comprising a threaded sleeve mounted on the shaft so as to move longitudinally but provided with means for preventing rotation, a threaded nut surrounding said sleeve and adapted when rotated to move the sleeve longitudinally.

11. A hoisting device comprising a shaft, a drum loosely mounted thereon, a connecting mechanism for operatively connecting the drum with the shaft, a controlling device for controlling said connecting mechanism comprising a threaded sleeve mounted on the shaft so as to move longitudinally but provided with means for preventing rotation, a threaded nut surrounding said sleeve and adapted when rotated to move the sleeve longitudinally, an eccentric on said nut, a brake mechanism for the drum and a connection between said brake mechanism and said eccentric whereby the said brake mechanism is operated when the nut is rotated.

HUGH DYER.
